The ornamental design for a lamp module for a modular lamp, as shown and described.

DESCRIPTION

FIG. 1 is a perspective view of a lamp module for a modular lamp in accordance with our new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures illustrate portions of the modular lamp that form no part of the claimed design.
